UNITED STATES PATENT OFFICE.

ELMER M. VAN BUREN, OF BRONXVILLE, NEW YORK.

TRAFFIC LIGHT.

Application filed March 4, 1924. Serial No. 696,723.

My present invention is shown as embodied in a highway traffic light of the type intended to warn, signal or direct traffic by means of two-way, three-way or four-way 5 shining beams, but certain features of the invention may be found useful in other connections, as, for instance, in railway or other signal lights.

One object of the invention is to provide a 10 simple, durable and cheap construction and arrangement, whereby the source of light employed for the signaling beams may be utilized to produce also an effective downward illumination, preferably somewhat diffused so that when the lamp is mounted on a post or pedestal of usual or desired type, 15 the post will be illuminated on all sides and will be practically shadowless. Preferably, the source of light is a single centrally located electric bulb having a high power filament or other luminous body of small mass which can be located substantially in the 20 axis of a plurality of the horizontally projecting lenses. In cases where the lamp is 25 symmetrically constructed and supported, as is highly desirable for artistic and structural reasons, this brings the source of light in alignment with the top of the post or pedestal whereon the lantern is mounted and 30 in practice the source of light is of small size as compared with the top of the post. Hence, even though the bottom of the lantern be open, the top of the post naturally 35 casts a dense shadow on the post, its pedestal and even for a substantial distance around the latter.

This is highly undesirable, because a light 40 located at the proper height, even though it be operated as a flasher light to attract attention, may escape notice under adverse weather conditions and in any event gives no sufficient warning of the size of the massive pedestal by which it is customarily supported. Moreover, any warning or instruction 45 signs carried by the post are invisible unless special lighting is provided.

To meet these conditions, my invention 50 contemplates forming the entire bottom of the lantern of very open construction, preferably employing sheet metal spider supports arranged edgewise to the light so that they are practically shadowless and preferably also eliminating the post shadow by employing a downward reflector which is 55 symmetrically formed with respect to a vertical axis in which the post and the lumi-

nous element of the lamp is located. In certain cases this reflector may be an ordinary parabolic reflector with mirror reflecting surfaces, such as is employed for ordinary head lights or search lights of automobiles. In such case a most intense downward light will result. Usually, however, this will be found undesirable, since an intensely illuminated area or field of light is blinding 60 and renders it difficult to see other objects, particularly those beyond or near the intensely illuminated area. For these and other reasons, I prefer to provide the downward reflector with a white reflecting surface 65 rather than with an image-reflecting surface. In such case, the area of illumination and its intensity may be predetermined by the axial depth of the reflector below the light or may be adjusted by relative movement of reflector and lamp to bring the luminous source at any desired position along the axis of the reflector.

In the specific form shown, the mouth or open bottom of the reflector extends substantially below the level of the horizontal beams projected through the lenses and the reflector is provided with openings of suitable area and location through which the light radiates along the axes of the lenses. 75 The area and location of the opening may be such that the reflector has the function of a lens diaphragm.

In certain cases the horizontal lens beams may be omitted since a properly arranged 80 downward reflector lamp at the proper height, with a white or diffuse reflecting surface, may be used to illuminate the pedestal posts and signs with a strong light which 85 has no sharp shadows.

The above and other features of my invention may be more fully understood from the following description in connection with the accompanying drawings, in which

Fig. 1 is a schematic view of the pedestal, 100 post and lantern, showing a desirable area of downward full illumination and also surrounding areas of penumbra or diminishing illumination;

Fig. 2 is a top plan view of the structure 105 shown in Fig. 1;

Fig. 3 is a vertical section showing the lantern and its mount on the supporting post;

Fig. 4 is a section on the line 4, 4, Fig. 3, 110 showing the skeleton support constituting the open bottom of the lantern;

Fig. 5 is a side view of a modification.

In the particular form shown in Figs. 1 and 2, the support for the light comprises a massive pedestal, 1, which may be of concrete, say, 30 inches square and 8 inches high, provided at the corners with cylindrical fender posts, 2, 2, and having at the center thereof frusto-pyramidal socket support, 3, in which is embodied a socket tube, 4. This tube may be a 2-inch iron pipe anchored in the cement by means of an iron cross-bar, 5, which also serves as the bottom of the socket for post 6. Post 6 may be an ordinary 1 1/2 inch iron pipe, the exterior of which will just fit the 2-inch socket pipe. The post tube, 6, may be, say, 5 feet high and carries at the upper end thereof the lantern, 7, provided with the coaxial projector lenses, 8, 9, adapted to project more or less divergent beams within desired limits indicated by the lines 8, 8^a and 8, 8^b in the one case, and 9, 9^a and 9, 9^b in the other case. As shown in Fig. 1, there may be a third projector lens, 10, at right angles to the axis of 8, 9 and, as shown in Fig. 2, there may also be a fourth lens, 11, coaxial with 10.

The post, 6, may carry a suitable sign as, for instance, the target, 13, with suitable legends, in this case, "Keep to the right", etc.

As indicated in Fig. 1, the lantern is arranged to project light downward in such a way as to effectively illuminate the post 6, pedestal 1, and a desired surrounding area such as would be used by a traffic officer when on duty. This light indicated by the lines 7, 7^a and 7, 7^b, will not be as sharply defined as said line would indicate, there being a surrounding annular zone of desired extent in which the illumination is progressively less intense. Though this zone is more or less indefinite, its possible extent may be indicated by the dotted lines 7, 7^a and 7, 7^b. A characteristic feature of the illumination with the preferred form of the device is that the equal-illumination areas are annular; that the illumination in the central portion of the circle is uniform and that the areas of diminishing illumination are also annular. In this way it becomes safe to have the central area very effectively illuminated without danger of blinding the vision with reference to points beyond and near the lighted area.

A suitable construction for the lantern 7, whereby the above effects may be produced, is illustrated in Figs. 3 and 4. The casing and lateral lenses may be of any known or desired construction. As shown, it comprises a cylindrical shell, 17, which may be of galvanized sheet iron or brass having lens holders 18, 19 for lenses 8, 9. The bottom by which it is supported on the pipe, 6, consists of sheet metal arms, 20, 20, radially connecting the socket cylinder 21, with the case, 17. In the special form shown in Fig. 4, the cylinder 21 is formed by integral extensions

of the arms, 20, each extension forming a quadrant of the cylinder, which is held together by rivets 22, securing the overlapped ends of the extensions. The outer ends of arms, 20, have integral bent portions which are secured by rivets, 23, to casing, 17. The top of the cylinder socket is formed by bent over portions, 24, 24, which engage the top end of the pipe 6. As will be noted, arms 20 taper, being very wide at the bases where they join socket 21, so that they have great vertical strength though relatively thin and offering very little obstruction to downward light.

The lamp bulb, 25, is supported from above in such manner that its light radiating element, 26, is substantially in the axis of lenses, 8, 9, and also in the axis of lenses, 10, 11, when the latter are used. For purposes of my present invention element 26 is also in the axis of the pipe 6, and the casing 17. The bulb, 25, is secured in socket, 27, mounted on an insulated support indicated as a circular piece of wood, 28, secured by screws, 29, 29, in a deep flange, 30, which fits the interior of casing, 17. This flange is bent at the top and secured by rivets, 31, to a conical roof or cover piece, 32. The close fit of the deep flange 29 is sufficient securing means for the cover but additional latches may be used if desired.

The means for downwardly diffusing the light from source, 26, while at the same time permitting proper illumination through the lenses, 8, 9, is a reflector, 33, supported by arms, 34, depending from the cover member, 28. The reflector, 33, has a central axial opening, 35, through which the neck of the lamp, 25, projects and side openings, 36, through which the light shines on the lenses, 8, 9. The reflector extends downward far enough so that its lower edge covers the lowermost portion 38, of the lens supports, 18, 19, thereby limiting the light available for a lens beam to that which shines through the opening, 36, with the well known effect of rendering the latter beam more definite.

The reflector might extend lower but part of the lantern body, at 46, below the mouth of the reflector 33, is preferably utilized as reflector surface by having it painted or enamelled white, like the inside of the reflector and in certain cases the entire inside of the lantern body may be thus painted or enamelled, in which case the reflector 33 could be omitted. Where there are four lenses, however, they render considerable areas of the lantern body unavailable for reflecting purposes and the use of a reflector with the much smaller openings 36 is preferable for this and various other reasons.

The lamp socket 27, may be connected with the lighting circuit through wires, 40, 41. As shown, these wires, which extend

upward, are connected to binding posts on a casing 45 which may contain a thermostatic flasher of the usual construction. The wires extend downward through slot 44, in 5 reflector 33 and to the open top of post pipe, 6, thence through the interior of post pipe, 6, and socket pipe, 4, to any suitable underground conduit leading from the bottom of the latter. Detachable couplings for the 10 wires may be provided at suitable points, as for instance at 45, Fig. 3, or at the bottom of the lantern or the top of socket pipe 4.

The interior of the lantern is readily accessible by simply lifting the cover which 15 carries with it the bulb and the reflector so that it takes but a moment to renew the former or clean the latter.

As shown in Fig. 5, the upper support 28 20 may be carried by the base support 20, 21, 22, by means of uprights 20^a, 20^a, forming a sort of cage. In such case, the body of the lantern including cylinder 17, lens holders 8, 9, 10, 11, and the cover piece 32, will 25 be a unitary shell with an open bottom so that it is removable and replaceable by simply sliding it vertically without disturbing any of the parts that are carried by the cage. It may be detachably secured to the 30 base ring by bolts, so that the shell becomes structurally rigid with the base and serves as protection for the cage and parts carried thereby.

I claim:

25 1. In a traffic signal device, a supporting post, an open bottomed lantern supported on the top of the post, a light source within the lantern, an open bottomed reflecting means mounted within the lantern and surrounding said light source for reflecting light downwardly in a cone of light about said post, and an opening in the reflecting means for permitting light from said source to be laterally projected.

45 2. In a traffic signal device, a supporting post, an open bottomed lantern centrally supported on the top of the post, a light source above said lantern positioned within the top of the post, an open bottomed reflecting means positioned within said lantern and surrounding said light source and extending below said light source for reflecting light downwardly in a cone of light about said post and inwardly and an opening in the reflecting means for permitting lateral projection of light from said light source.

3. In a traffic signal device, a supporting post, an open bottomed lantern supported 60 on the top of the post, a removable top on said lantern, a light source, an open bottomed reflecting means surrounding said light source for reflecting a cone of light downwardly about said post, means mounting said light source and said reflecting

means in the removable top, and an opening in the reflecting means for permitting lateral projection of light from said light source.

4. In a traffic signal device, a supporting post, an open bottomed lantern centrally supported on the top of the post, a removable top for said lantern, a light source, an open bottomed reflecting means surrounding said light source and extending below said light source for reflecting light downwardly in a cone of light about said post and inwardly, means mounting said light source and said reflecting means in the removable top, and an opening in the reflecting means for permitting lateral projection of light from said light source. 70 75 80

5. In a traffic signal device, a massive pedestal, a post thereon, an open bottomed lantern of greater diameter than the post centrally supported on the upper end of the post, a removable top for said lantern, a light source in the lantern in line with the axis of the post and of less diameter than the post, open bottomed reflecting means surrounding the light source and extending below said light source, and having the open bottom substantially concentric with the post for reflecting light downwardly and inwardly, side openings in said reflecting means for permitting lateral projection of light beams from said light source, and means mounting said light source and said reflecting means in the removable top. 85 90 95

6. In a traffic lantern, a casing, a projector lens mounted therein, a source of light, means mounting said light source approximately in the axis of the lens and in the vertical axis of the casing, a central support, a base for the lantern comprising thin arms extending from the casing to the central support, an open bottomed reflecting element mounted in the casing and surrounding the light source and having the open bottom substantially concentric with the central support, and extending below said light source, and having an opening adjacent the lens, whereby light is projected through the lens and reflected downwardly and inwardly. 100 105 110 115

7. In a traffic lantern, a casing, a projector lens mounted therein, a source of light, means mounting said light source approximately in the axis of the lens and in the vertical axis of the casing, a central support below said source, shading a substantial central area, an open work base for the lantern, extending from the casing to the central support, an open bottomed reflecting element mounted in the casing surrounding and extending below the light source and having the open bottom substantially concentric with the central support, and having an opening adjacent the lens, whereby light is projected through the lens and reflected 120 125 130

downwardly and inwardly to illuminate areas which the central support shields from the direct rays of the light source.

8. In a traffic signal device, a post, and means supported above said post comprising a unitary source of light for throwing a cone of light about said post and for project-

ing lateral light beams substantially at right angles to the axis of the post.

Signed at New York, in the county of ¹⁰ New York, and State of New York, this 3rd day of March, A. D. 1924.

ELMER M. VAN BUREN.
